UNITED STATES PATENT OFFICE.

MARTIN W. WALKER, OF OSSINING, NEW YORK.

CLOTHES-DRIER.

1,139,605.

Specification of Letters Patent. Patented May 18, 1915.

Application filed August 21, 1913. Serial No. 785,999.

To all whom it may concern:

Be it known that I, MARTIN W. WALKER, a citizen of the United States, residing at Ossining, in the county of Westchester and 5 State of New York, have invented certain new and useful Improvements in Clothes-Driers, of which the following is a specification.

This invention relates to improvements 10 in clothes driers and has to do more particularly with that class of clothes driers that are suspended adjacent windows and usually at an elevation from the ground.

One of the objects of the invention is to 15 provide a clothes drier whereby the clothes may be pinned or otherwise fastened upon racks or hangers and adapted to be thereafter projected from the interior through the window into an out of doors position.

20 A further object is to provide clothes hanger or rack supporting means consisting of a part fixedly mounted in an exterior position and an extension part adapted to project into the interior whereby a plurality of 25 racks or hangers may be in the interior and projected along the extension outwardly in suspended engagement with the exterior part, and in this connection, this feature also provides means whereby a plurality of 30 racks may be filled with clothes in the interior of a compartment without opening the window and thereafter shifted on said extension into suspended relation with the exterior part.

35 A further novel feature resides in providing racks or sections adapted to interlock so that pressure in either direction on the innermost of the sections, will serve to advance or to permit of withdrawing and taking 40 in one section at a time, thereby leaving the remaining sections suspended in an exterior position.

Further objects and novel features of the invention will be more fully described in 45 connection with the accompanying drawings and more particularly pointed out in and by the appended claims.

In the drawings: Figure 1, is a perspective sectional view of a window, looking 50 from the exterior, and showing one form of the device of my invention applied thereto. Fig. 2, is a sectional view showing the manner of mounting an extension guide in an interior position. Fig. 3, is an end view 55 showing an improved form of a section stop.

Fig. 4, is a perspective view of the inner end of the exterior guide support. Fig. 5, is a cross sectional view on line 5—5 of Fig. 1. Fig. 6, illustrates the adjacent ends of two 60 rack-supporting sections, with the same in perspective.

Like characters of reference designate similar parts throughout the different figures of the drawings.

As illustrated, 1, designates the wall of a 65 building in which a window frame 2, is disposed, upper and lower sashes being indicated at 3 and 4.

The device embodying my invention may be anchored in position by supporting 70 means in the form of a bracket 5, which is shown secured to a portion of the building structure. An additional supporting means may be provided in the form of a tension cable 6, which is shown secured to 75 the building at 7, and to the outer end of the device at 8.

An exterior supporting guide 9, is suspended by the bracket 5, and the cable 6, 80 exteriorly of the window and near the upper portion thereof. As shown more particularly in Fig. 5, the supporting guide is tubular in form and along the lower periphery thereof I provide a longitudinally disposed slot, the walls thereof being indicated at 10. It will be seen by reference 85 to Fig. 1, that the inner end of the guide support 9, is disposed adjacent to but exteriorly of the window, the purpose of which will presently appear.

A plurality of clothes rack supporting 90 sections 11, are provided with flanges 12, which engage the interior of the support 9, and webs 13, which depend through the slot in said guide, as clearly shown in Fig. 95 5. Alternate ends of the webs 13, are provided with coupling means which may be in the form of hooks 14, adapted for engagement in a manner which will be clear by reference to Fig. 6, and engagement of 100 the webs 13, with the walls 10, will serve to hold the sections securely in slidably engagement with the guide support, as illustrated. Each section 11, is provided with a clothes rack 15, which may be only 105 slightly less in length than the width of the window so as to provide for the greatest possible capacity. If the clothes racks are formed of wire, the same may be mounted in supporting relation with the sections 11, 110

by looping the wires of the rack through openings 16, in the webs 13, as indicated at 17.

The sections 11, may be slid into and 5 along the guide support 9, in end to end relation, and in order to prevent the same from sliding out of the inner end of the support 9, I provide a stop 18, which may be in the form of a disk pivoted at 19, to 10 the bracket 5. The outer end 20, of the support 9, will always be closed so as to prevent the sections from sliding outwardly therefrom.

An extension or loading member is provided in the form of a guide support 21, 15 which may be tubular in form and preferably of the size of the guide support 9. Said loading guide 21, is provided with a longitudinally disposed slot 22, and an end 20 closure 23, having a stop 23'. A sleeve 24, is secured to said extension 21, and is provided with a slot 25, adapted to register with the slot 22. When the extension is not in use it may be hung upon a support 26, secured to the interior as indicated at 25 27. The support 26, will be shaped to fit the interior of the sleeve 24.

When the extension is positioned for use, the stop 18, will be swung laterally and the 30 sleeve 24, will be telescoped over the inner end of the support guide 9, and against the terminal 28, of the bracket 5, such terminal being arcuately formed to embrace the said inner end of the guide 9 and being secured 35 thereto. In order to non-rotatively engage the extension 21, with the support 9, I provide the latter with a stud 29, adapted to engage a recess 30, in the sleeve 24, this means also serving to hold the slots of the 40 telescoped supports in registry.

The extension 21, may be bent downwardly at its inner end so as to be accessible to the user without necessitating any stand, or in other words, the user will have access 45 to the extension while standing on the floor.

If the clothes to be dried are to be projected through the window with the parts in position in Fig. 1, the window may be partially closed by providing a suitable 50 cloth closure in cases where the weather is very cold.

Several racks will be hung with clothes, by any means such as clothes pins, and the sections will be inserted end to end into 55 the extension 21, until the desired number of sections with their racks, have been filled. As the sections are inserted, they will be coupled in hooked relation and when the sections are in place and pressure applied, the innermost section will advance all 60 of the other sections through extension 21, and into supporting relation to the exterior guide 9. The extension 21, may then be removed and the stop 18 will fall by gravity 65 into a locking position so as to prevent the

sections from sliding out of the inner end of support 9.

If desired, I may provide a cord 31, for the outermost section so that if only one or two sections, with their racks, have been used 70 and forced outwardly by a rod or like implement, they may be withdrawn into an accessible position by the cord 31. At any rate the extension 21, will be again inserted in place for the removal of the racks. However, if the support 9, has been completely 75 filled with rack sections, the same may be drawn inwardly by pulling in the innermost section, by reason of the fact that the sections are coupled together. If the 80 weather is very cold, all the sections with their racks may be supported on the extension 21, while the same is supported in the interior position shown in Fig. 2, while the window is closed, and then the upper sash 85 may be lowered and the extension telescoped onto the support 9, so that the clothes sections can be forced outwardly into the support 9.

It is believed that the utility and advantages of the invention and the several ways in which the device of my invention can be used, will be clear from the foregoing description, and while I have herein shown and described one specific form of my invention I do not wish to be limited thereto except for such limitations as the claims may import.

I claim:

1. In a clothes drier, an exterior support 100 projecting from a window, a plurality of sections attached for slidable engagement with said support in end to end abutting relation, clothes supporting racks for said sections, and an extension support adapted 105 for removable attachment to said exterior support and for a similar accommodation of said sections.

2. In a clothes drier, an exterior slotted tubular support disposed adjacent a window, 110 an extension support adapted to be removably aligned with said exterior support through said window, flanged sections adapted to be fed through said extension into said exterior support, and clothes racks 115 carried by each section.

3. In a clothes drier, a tubular exterior support disposed adjacent a window, a loading support removably connecting therewith through said window, clothes suspension 120 sections slidable through one into the other of said supports, and means pivotally mounted on first said support to prevent movement of said sections therefrom upon removal of second said support.

4. In a clothes drier, an exterior tubular support, means for suspending the same adjacent to but outside of a window, a tubular extension support adapted to telescope the exterior support and project through the 130

window, said supports having registering slotted portions, and clothes suspension means adapted for sliding engagement through the slotted portions of said supports from the interior along said extension to said exterior support, substantially as described.

5. In a clothes drier, a tubular slotted support, a sleeved and removable extension for 10 said support and registeringly slotted, flanged sections adapted to be interiorly accommodated within said support and extension, webs formed on each section to depend through said slots, and coupling hooks 15 formed integrally on the extremities of each web to interconnect said sections.

6. In a clothes drier, suspension means disposed exteriorly of the window and near the upper portion thereof, a clothes drying 20 device slidably supported by said means, and an extension or loading means adapted for attachment to said exterior means in alined end to end relation for projection through the window and extending downwardly 25 interiorly of the window to render the same accessible from the floor of the compartment, substantially as described.

7. In a clothes drier, a tubular support provided with a longitudinally disposed slot, 30 means for anchoring said support with one end thereof adjacent the upper portion of a window and exteriorly thereof, a tubular extension loading member provided with a longitudinal slot and having means for telescoping said exterior support for projection 35 of the loading member through the window, a plurality of clothes supporting devices slidable in said support and member and projecting therethrough, and means attached to the outermost of said devices for 40 drawing the same inwardly through the window, substantially as described.

8. In a clothes drier, a tubular support

fixed near the top of a window with its outer end projecting from the window and its inner end adjacent to the exterior top of the window and said support being longitudinally slotted on its lower periphery, and a loading extension comprising a tube having means for telescoping the tubular support to 45 mount the tube thereon in end to end relation, said tube having a slot for registry with the slot in said tubular support and the inner end of the loading tube being bent downwardly inside of the window, and clothes- 50 supporting means slidable in said tube and tubular support and depending through said slots, substantially as described.

9. In a clothes drier, a tubular structure 55 mounted to extend outwardly from a window and longitudinally slotted, and clothes supporting means slidable in said tubular structure including removably connected sections opposite arc flanges formed on each section to contact with the interior of said 60 tubular structure, and apertured webs formed on said sections and depending through said slot.

10. In a clothes drier, a tubular slotted support disposed adjacent a window, a 65 sleeved removable and similarly slotted extension therefor, projecting through said window, flanged sections adapted to be accommodated interiorly of said support and extension, apertured webs formed on each 70 section to depend through said slots, integral coupling means between adjacent section webs, and clothes racks looped through the depending web of each section.

In testimony whereof I affix my signature 75 in presence of two witnesses.

MARTIN W. WALKER.
